UNITED STATES PATENT OFFICE

HERMANN H. LOTT, OF WEBSTER GROVES, MISSOURI

JEWELRY BRACELET

Application filed January 30, 1928. Serial No. 250,569.

This invention relates generally to jewelry-bracelets and, more particularly, to a certain new and useful improvement in bracelets of strap or band type adapted for connection to a wrist watch or the like.

In bracelets of the type stated, it is highly desirable that there shall be very little, if any, possibility of the strap or band becoming accidentally unfastened or detached from the watch, and the bracelet unit hence includes an efficient latch that may be conveniently and easily operated either in engagement with, or disengagement from, the watch. A second desiratum is that the inner side or face of the bracelet, where it bears upon or rubs against the wrist, shall be smooth and plain, so as to cause no discomfort to the wearer. A third feature is that the bracelet shall be readily adjustable in length to fit or accommodate different wearers or users.

My invention has accordingly among its objects the provision of a jewelry or watch-bracelet which shall be neat and attractive in appearance and economical and durable in construction, which shall embody the desirable features stated, and which shall be efficient and satisfactory in use.

And with the above and other objects in view, my invention resides in the novel features of form, construction, arrangement, and combination of parts hereinafter described and pointed out in the claims.

In the accompanying drawing,—

Figure 1 is a plan view of a link-bracelet embodying my invention, illustrated in operative connection with a wrist-watch;

Figure 2 is a front elevational view of the same;

Figure 3 is an enlarged fragmental longitudinal broken sectional view of the bracelet, taken approximately along the line 3—3, Figure 4;

Figure 4 is a similar view, taken approximately along the line 4—4, Figure 3;

Figure 5 is an enlarged plan view of the blank from which the latch element is formed and constructed;

Figure 6 is a perspective view of the shell

of one of the end or watch-engaging members of the bracelet;

Figure 7 is an enlarged plan view of an element of one of the watch-engaging or end-links of the bracelet;

Figure 8 is an enlarged plan view of one of the bracelet link-members, the shell thereof being removed; and

Figure 9 is an enlarged plan view of the blank from which one of the elements forming the link is made.

Referring now more in detail and by reference characters to the drawing, which illustrates a preferred embodiment of my invention, the bracelet includes end or latching links A, a selective number of intermediate links B, and a so-called middle or central link C located somewhere within the series of links B, the several links being adapted for detachable connection one with the other in the formation of a flexible strap or band intended to be worn in encircling relation about the wrist and to support a watch or other ornament D, as shown.

Each intermediate link B includes an open-end shell or casing b preferably approximately rectangular in shape and slightly curved or arched longitudinally. Disposed within the shell b, is an element d formed of a suitable strip of spring metal folded centrally upon itself to include a pair of superposed slightly spaced yielding or spring-legs, 1, 2, the former being provided with an elongated opening 3 extending preferably from the end-bar 4 to slightly beyond the line of fold, and the latter being provided preferably integrally with a spring-prong 5 of preferably rectangular contour and having its free end presented toward the line of fold and downwardly or inwardly toward the opening 3 in the other leg 1.

e designates a co-operating element likewise formed of suitable strip spring metal. The element e is of equal width with element d and adjacent one end is oppositely slotted inwardly, as at 6, and thereby provided with pintles 7, which are received and held within the folded end of element d for hingedly or pivotally interconnecting the elements d and

100

e, as best seen in Figure 8. Formed in the element *e*, is a preferably rectangular opening 8, the outer wall of which, to facilitate link-disengagement, as more fully later appears, is recessed, as at 9, thereby also providing corners or shoulders 10, 10, for prong-engagement, as also more fully appears, the opening 9 being of a size suitable to receive the prong 5 of an adjacent link 5 B for detachably fastening or securing the links endwise together. It may be here added that shell *b* is of size to snugly accommodate the element *d* and upon its inner wall is formed preferably integrally with an 10 inwardly presented prong 11 adapted to project into opening 3 and engage end-bar 4 to secure the element *d* and its pivotally connected element *e* operatively in position, as seen in Fig. 3, the hinge-connection between the elements *d* and *e* being then disposed outwardly of and at an end of the shell *b*, so as to permit relatively free hinge-movement between the several respective 15 links of the bracelet.

20 The elements *d* and *e* thus form a connector for the link, and accordingly, when it is desired to interconnect adjacent links B, the projecting element *e* of one link is endwise slidably inserted into the shell *b* and between the legs 1, 2, of the other link, the prong 5 of the second or other link then springing into link-engaging relation with the shoulders 10 of the inserted element *e*.

To detachably disconnect the links B in 25 order to remove or substitute a link, I preferable employ a tool E provided at its forward end with a depending flange 12 provided at preferably the center thereof with a projecting tooth or pin 13. This pin 13 30 of tool E is adapted to be inserted through an aperture 14 of the back-plate or wall of the link shell to depress the corresponding spring or prong 5 out of engagement with the shoulders 10 to release the particular 35 strap-element *e*. Tool E remaining in its described operative engagement with the link, the said strap-element *e* cannot be at once entirely disconnected or detached from the link, due to the engagement of tool E 40 at its pin 13 with said strap-element; the connecting strap-element *e*, however, may now, due to said recess-continuation 9 of spring 8 of the strap-element, be moved outwardly relatively to the link a limited distance 45 depending upon the depth of the recess 9. The connecting strap-element *e* being so moved outwardly, the shoulders 10—10 thereof will ride upon the said spring or prong 5 and thereby, on tool E being now 50 removed from engagement with the link and also with said strap-element, hold the spring 5 in depressed or unlocking position, whereupon, as will be evident, the connecting-strap-element may be entirely detachably 55 disconnected or disengaged from the link.

It will thus be seen that, while a link B and a connecting-member *e* are readily and easily detachably connected, the links B are, when in operative connection one with the other, firmly and securely locked together 70 and that they cannot be detachably disconnected or separated except by positive operation on the part of the wearer or user. Any desired number of links B may thus be readily detachably connected by means of 75 their connectors to form a complete or finished bracelet of the required size, as illustrated in Fig. 1, the bracelet so formed being, due to the hinges of their connectors, exceedingly flexible to meet all requirements. 80

To permit engagement between a series of connected links B with opposite end-links A, each of which is equipped with a connector-element *e*, I interpose at any suitable point within the series of links B, a so-called middle link C, which includes merely a shell *b'* for housing a connector-element *e* of a link *d* projecting from a contiguous link B and a co-operative connector-element *e'* of a link *d* projecting from the other contiguous link 85 B, the element *e'* having a spring-prong 5' for engagement with the shoulders 10 of the element *e*. The shell *b'* has similarly a wall-opening or aperture 14 for accommodating 90 the pin or tooth 13 of the link-disengaging tool E in detaching the spring-prong 5' from its so engaged connector-element *e* to 95 permit separation of the contiguous links B from the middle link C.

Each of the end-links A comprises a somewhat elongated shell *a* having for the greater part of its length the approximate rectangular flaring contour best seen in Figure 6, shell *a* including opposed relatively narrow side walls 15 and opposed front and back walls 16, 17, respectively, the latter terminating at its forward end 18 in approximately the plane of the forward ends of the side walls 15 and the former having a preferably integral continuation bent or rounded rearwardly upon itself in the formation of a hook 19 whose beak or bill 20 is disposed adjacent the end 18 of rear wall 17 in the provision of a relatively narrow slot, as at 21, for accommodating the end-bar 22 105 of a watch or other ornament D in the engagement therewith of a link A. 110

Forming part of link A, is a latch *f* constructed preferably of a blank of suitable spring sheet metal having the contour best seen in Figure 5 and comprising a relatively wide mid-section 23, a short narrow end-portion 24, and an elongated end-portion 25. Adjacent the short end-portion 24 and oppositely upon its opposite sides, the mid-section 23 is slotted inwardly, as at 26, 26, and intermediate the open-end slots 26 is provided with a closed end slot 27. The blank so formed is then folded or bent into 120 approximate cylindrical or tubular shape in 125 130

the formation of the latch *f* of a size to fit snugly within the confines of hook 19 and underlie in closing relation the slot 21, as best seen in Figure 3, with the free end of the portion 25 bent backwardly and projecting through an opening 28 in shell *a* to provide a finger catch 29, for purposes shortly appearing, the shorter end-portion 24 bearing upon the shell front wall 16 at a point adjacent said opening 28, so that, when the catch 29 is gripped and actuated (to the right in Figure 3), the latch *f* will rock about the end 24 as a pivot and thereby open the slot 21 to freely permit engagement and disengagement with the watch or other ornament D.

For retaining the latch *f* operatively within the hook 19 of shell *b*, is a holding member *g* having the form best seen in Figure 7, which member, as there shown comprises an end-bar 30, a central leg 31, and side legs 32, all said legs trending in the same direction from end-bar 30, the legs 32 being provided at their free ends with hooks 33 adapted to loosely interlock with the slots 26 of the latch-member *f*, and the central leg 31 being adapted to fit at its free end in the slot 27 of the latch-member.

Slotted at one end to movably embrace the several legs of member *g*, as best seen in Figure 4, is a looped or closed connector-element *d'*, pivotally connected to which at its other end is a co-operating connector-element *e*, and coiled on the central leg 31 and abutting at one end against the slotted end of the strap-loop *d'* and at its other end against the end bar 30, is a spring 34 for yieldingly permitting slidable movement between the latch-retaining member *g* and the link-connector-element *d'* for facilitating fit of the bracelet upon the wrist. It will, of course, be understood that the connector element *d'*, latch-member *f*, and the latch-retaining member *g* are first operatively connected together, then inserted as a unit endwise within the shell *a*, and retained as a unit within the shell by means of the hook 19 then formed out of and by the forwardly extending continuation of the front shell-wall 16.

Thus I provide a strap-bracelet which efficiently answers all requirements and fulfills the objects hereinbefore stated.

I am aware that changes in the form, construction, arrangement, and combination of the several parts of my new bracelet may be made and substituted for those herein shown and described without departing from the nature and spirit of my invention.

Having thus described my invention, what I claim and desire to secure by Letters Patent is:

1. In a jewelry-link, a shell comprising connected side and opposed front and back walls, the front wall having a slot and a

hook continuation, the latter terminating adjacent the end of the back wall to provide an ornament-bar accommodating opening, in combination with a latch-member of tubular formation embraced by the shell and its said hook-continuation to normally underlie and provide a closure for said opening, said latch-member having a pivot-bearing upon the inner face of the shell front-wall for rocking movement and also having an actuating extension projecting outwardly the shell through said slot for finger-engagement. 70

2. In a jewelry-link, a shell comprising connected side and opposed front and back walls, the front wall having a slot and a hook continuation, the latter terminating adjacent the end of the back wall to provide an ornament-bar accommodating opening, in combination with a latch-member of tubular formation embraced by the shell and its said hook-continuation to normally underlie and provide a closure for said opening, said latch-member having a pivot-bearing upon the inner face of the shell front-wall for rocking movement and also having an actuating extension projecting outwardly the shell through said slot for finger-engagement, and means for retaining the latch-member rockably within the shell. 80

3. In a jewelry-link, a shell comprising connected side and opposed front and back walls, the front wall having a slot and a hook continuation, the latter terminating adjacent the end of the back wall to provide an ornament-bar accommodating opening, in combination with a latch-member of tubular formation embraced by the shell and its said hook-continuation to normally underlie and provide a closure for said opening, said latch-member having a pivot-bearing upon the inner face of the shell front-wall for rocking movement and also having an actuating extension projecting outwardly the shell through said slot for finger-engagement, and means for retaining the latch-member rockably within the shell, said means including a holding-member having connection with the latch-member, and a link-connector element embracing the holding-member, said means being housed within the shell and the holding-member being movable longitudinally the shell relatively to the connector element. 100

4. In a jewelry-link, a shell comprising connected side and opposed front and back walls, the front wall having a slot and a hook continuation, the latter terminating adjacent the end of the back wall to provide an ornament-bar accommodating opening, in combination with a latch-member of tubular formation embraced by the shell and its said hook-continuation to normally underlie and provide a closure for said opening, said latch-member having a pivot-bearing 120

ing upon the inner face of the shell front-wall for rocking movement and also having an actuating extension projecting outwardly through said shell through said slot for finger-engagement, and means for retaining the latch-member rockably within the shell, said means including a holding-member having an end-bar and a plurality of spaced legs projecting from the end-bar, some of said legs engaging the latch-member, a looped connector element loosely embracing the holding-member and having a portion in opposed relation to said end-bar, and a spring coiled on a leg of the holding-member and abutting against said end-bar and the connector element for yieldingly spacing the one from the other, the holding-member being yieldingly movable longitudinally the shell relatively to the connector element.

20 In testimony whereof I affix my signature.
HERMANN H. LOTT.
